ALBERT L. LAMBERT, OF NARBETH, PENNSYLVANIA, ASSIGNOR TO HEINTZ MANUFACTURING COMPANY, OF PHILADELPHIA, PENNSYLVANIA, A CORPORATION OF PENNSYLVANIA.

METHOD OF FORMING AXLE HOUSINGS.

Application filed December 15, 1923. Serial No. 680,793.

This invention pertains, in the main, to the construction of axle housings and it has to do in particular with the formation of housings which are employed with the rear axles of 5 automobiles. Probably the greatest use of my invention will be in constructing axle housings but I desire to be understood that it is not my intention to be so limited in the scope of use of the essentials of my invention 10 for it may be employed in constructing metal articles or parts thereof which are used in fields entirely foreign to that of the automobile industry.

The primary aim of my invention is to construct metal articles or parts in an entirely 15 new and novel manner which materially reduces the amount of material heretofore used in constructing the same articles. By employing my improved method, I accomplish 20 the purpose of making an article or a part much lighter in weight while at the same time I have not reduced the strength of the article or part at any place where strength is essential.

25 A further and particular object of my invention is to construct an improved housing for the rear axle of an automobile which will be lighter in weight than those heretofore constructed to perform the same duty 30 and which will serve its purpose in a thoroughly satisfactory manner.

In the accompanying drawings, I have 35 illustrated an article in its various steps of manufacture, and the construction of this preferred article aptly shows the practice of my invention.

In the drawings, Fig. 1 is a top plan view 40 of a blank employed in forming an axle housing; the dotted lines representing the original shape of the blank;

Fig. 2 is a top plan view of a blank employed in forming an axle housing by my improved method; this view also shows the size of the blank after some of the steps of 45 my improved method of manufacture have been completed;

Fig. 3 is a side elevational view of the blank before being blanked and bent into final form;

50 Fig. 4 is a view of a complete housing for an axle;

Fig. 5 is a sectional view taken on the line 5—5 of Fig. 4;

Fig. 6 is a sectional view taken on the line 6—6 of Fig. 4;

Fig. 7 is a sectional view taken on the line 7—7 of Fig. 2 after the completion of one step of my improved method of manufacture;

Fig. 8 is a sectional view taken on the line 8—8 of Fig. 4;

Fig. 9 is a sectional view taken on the line 9—9 of Fig. 4;

Fig. 10 is a side elevational view of dies employed for stretching a portion of the 65 blank;

Fig. 11 is a sectional view taken on the line 11—11 of Fig. 10; and

Fig. 12 is a view of the base portion of the top die showing a means for holding the 70 blank from slipping during the stretching operation.

In describing my invention in detail, it will be of advantage to set forth one of the usual methods which have heretofore been employed in producing axle housings and for this purpose reference is made to Fig. 1. In this figure the dotted lines represent the outline of a rectangular flat sheet 1 of metal from which a top or bottom part or half of 80 an axle housing is formed. The original blank is cut or blanked to the shape outlined by the full lines of this figure, and it is then bent or formed into a shape represented in general in Fig. 4. The points 4 of the blank, 85 as shown in Fig. 1, engage like points of the other bent half of the axle housing as illustrated in Fig. 4. In the method heretofore employed it will be noted from Fig. 1 that there is a considerable amount of material 90 cut away from the original size blank to form the shape actually used, thus there is a large amount of waste as all of the material between the dotted and full lines is useless except to blank out the points 4.

A complete axle housing usually consists of two halves or parts 2 and 3 and after they have been bent into final form they are welded together and are then ready to enclose the axle sections and the bevel gears employed 100 therewith.

My invention has to do with an improved

method of forming the axle housing from unit pieces of material whereby the amount of waste is reduced and the weight of the finally formed housing is also reduced. Both 5 of these results are accomplished without in any way impairing the necessary strength of the housing. In forming a part or half of a housing, by my improved method, I take a single rectangular piece 5 of sheet metal represented by the lines 6 in Fig. 2, stretch the middle section thereof so that its outline will be that shown by the lines 7. From this stretched section I cut or blank the piece to the desired shape and outline which forms 10 points 8, and I then bend the half into the final shape as illustrated in Fig. 4. The flattened section as shown in Fig. 8 is preferably obtained by pressing or flattening the middle section that has been stretched. It is to be 15 understood that it is not necessary to flatten this portion of the housing unless desired. I have shown it flattened simply to illustrate the manner in which a particular design may be accomplished.

20 Any suitable means may be employed to stretch the metal sheet and I have shown one such means in Figs. 10, 11 and 12 which are particularly adapted to perform this step. The original sheet 5 is placed on a suitable 25 die 9 having a central channel 10 and it is then clamped in position by a cooperating die 11 which is moved into position as illustrated in Fig. 11. Any preferred means may be employed to hold the dies together. A 30 plunger 12 is then forced downward to stretch the material between the dies thus forming a cross sectional shape of the blank at its central portion as illustrated in Fig. 7. Since it is desirable to stretch only a certain length 35 of the blank near its center in order to obtain sufficient width to blank out points 8, I provide gripping dies 13 with roughened surfaces 14 which engage only predetermined lengths of the edges of the middle of the piece 40 and prevent slipping thereof. The lengths of these gripping surfaces may be noted in Figs. 45 10 and 12. The extensions of the piece which lie beyond the gripping surfaces are permitted to slide between the dies and are bent 50 into semicircular shape by the downward movement of plunger 12, as shown in Fig. 5. These extensions are known in the art as the 55 arm sections of the housing and are represented at 15 and 16. It will be noted that from this step in the method that only the 60 center of the central body section of the metal sheet is stretched along its smaller axis and that the edges of this section, which are held between the dies, remain at their original thickness. These edges are bent in the final bending operation to form flanges 17 of the 65 bowed out portion of the central section.

After the sheet has been stretched, it is 70 preferably flattened until it takes the shape 65 as illustrated in Fig. 3 and then it is cut

or blanked in the usual manner to form the desired shape which includes the points 8 so that when bent into final shape it will 75 form an axle housing of proper shape and dimensions. The sectional views in Figs. 5, 6, 8 and 9 illustrate the condition of thickness of the metal at the arm sections 15 and 16, at the beginning of the bowing of the central section and at the middle of the central section where it is shown to be of channel section as particularly illustrated in Fig. 8. It will be noted that the center 18 of the central section between the flanges 17 is of less thickness than the thickness of the flanges and of the remainder of the piece 80 or blank. As most of the strain, which develops during the operation of the vehicle in which a housing of this nature is employed will be taken by the flanges 17, it is not necessary that the center 18 of the housing shall be of equal thickness with those portions which are subjected to great strains. I therefore find that by decreasing the thickness of the material at this central body section 85 that it is possible to form a half of a housing from an original sheet of metal of much smaller dimensions than has heretofore been possible and I also find that the weight of the housing is thereby reduced. These are some of the particular advantages which are 90 derived from the use of my improved method in constructing a housing of substantially the same strength as housings heretofore produced and the use of this method accomplishes this purpose at a material reduction 95 in cost of the raw material.

It will be seen that by stretching a portion of an original blank of material that it is possible to make an article, or a part 100 of an article, from a much smaller blank 105 of material than has heretofore been possible and that the ease and operation of constructing the final shape of the article are very much enhanced. For this reason, I wish it to be understood that it is possible to employ my method to form other articles of manufacture, or parts thereof, in the manner which I have employed in forming axle 110 housings and thereby reduce the cost of production and also materially reduce the weight 115 of the article.

It is appreciated that certain modifications and changes may be made in my method of constructing metal articles and also that changes may be made to produce an 120 axle housing of somewhat different design but which include the essentials of my invention, and such variations are considered as being within the scope of my invention 125 which is outlined in the subjoined claims.

What I claim is:

1. The method of forming the bow portion of an axle housing, which consists in 130 expanding the longitudinal center portion only of an elongated sheet of metal so as to 130

widen and reduce the thickness of said center portion with respect to the adjacent side edge portions of said sheet.

2. The method of forming the bow portion of an axle housing, which consists in expanding the longitudinal center portion only of an elongated sheet of metal so as to widen and reduce the thickness of said center portion with respect to the adjacent 5 side edge portions of said sheet, and bending the sheet transversely into U-shape.

3. The method of forming the bow portion of an axle housing, which consists in expanding the longitudinal center portion 15 only of an elongated sheet of metal so as to widen and reduce the thickness of said center portion with respect to the adjacent side edge portions of said sheet, bending the sheet transversely into U-shape, and bending 20 the sheet longitudinally into bow form.

4. The method of forming part of an article which consists in the following steps,

stretching a portion of a metal sheet, cutting said sheet to predetermined size and outline, and bending the sheet into final form. 25

5. The method of forming part of an axle housing which consists in the following steps; stretching the central body section of a sheet metal blank, flattening the same, cutting the flattened blank, and bending it into final 30 form.

6. The method of forming part of an axle housing which consists in the following steps, clamping the edges of the central body section of a sheet metal blank between dies, 35 stretching the central section thereof which is not between the dies, substantially flattening the sheet after stretching, blanking the sheet between dies, and bending it into final form. 40

This specification signed this eleventh day of December, 1923.

ALBERT L. LAMBERT.
